UNITED STATES PATENT OFFICE.

CHARLES E. CATHER, OF WORCESTER, MASSACHUSETTS, ASSIGNOR TO UNITED STATES ENVELOPE COMPANY, OF SPRINGFIELD, MASSACHUSETTS, A CORPORATION OF MAINE.

DOUBLE ENVELOP.

1,385,114.

Specification of Letters Patent. Patented July 19, 1921.

Application filed December 16, 1919. Serial No. 345,393.

To all whom it may concern:

Be it known that I, CHARLES E. CATHER, a citizen of the United States, residing at Worcester, in the county of Worcester and 5 Commonwealth of Massachusetts, have invented a new and useful Improvement in Double Envelops, of which the following, together with the accompanying drawings, is a specification.

10 The object of my present invention is to provide a double envelop, or two envelops integrally connected, one of which may be adapted to contain an inclosure requiring first-class postage, and the other envelop 15 adapted to receive an inclosure requiring only second or third-class postage. In transmitting second or third-class matter through the mails it is desirable that the envelop containing the same should be of 20 unusual strength, as the inclosures are frequently bulky and of considerable weight. The envelop containing first-class matter should preferably be of that type known as an "outlook" envelop, or an envelop having 25 a window opening through which an address upon the inclosure may be read, and thereby serve as the address of both envelops.

I am aware that it has heretofore been 30 proposed to provide a double envelop whereby inclosures subject to different postal rates may be contained in separate wrappers which are connected together to avoid the liability of their separation during their transmission through the mails. By means of my 35 present invention I materially strengthen the envelop containing the second or third-class matter, I provide a window opening by which an address upon the first-class matter 40 may be easily read, and I preferably place the first-class envelop upon the back of the other envelop, leaving the face of the latter free to receive an address, thereby providing the address upon both sides, facilitating the 45 sorting and distribution of the mail.

In the accompanying drawings—

Figure 1 represents a blank in extended form from which my improved double envelop is made.

50 Fig. 2 represents the blank as partially folded.

Fig. 3 represents the completed envelop.

Similar reference characters refer to similar parts in the different figures.

Referring to Fig. 1 of the accompanying drawings, 1 denotes the body portion of the blank provided on one side with a side flap 2, and on the opposite side with a narrow side flap 3. At one end of the body portion 1 provide a closing flap 4 and a short distance from the opposite end of the body portion 1 I provide a window opening 5. Upon one end of the side flap 2 I provide a gummed sealing flap 6 and along the edge of the side flap 2 I provide a narrow strip 65 of adhesive material 7. The broken lines 8 and 9 denote the lines of fold of the first operation, as represented in Fig. 2. Said folding operation consists in turning over the side flap 2 upon the body portion 1, 70 thereby bringing the gummed surface 7 uppermost. The narrow side flap 3 is then folded upon the gummed surface 7, as represented in Fig. 2. Adhesive material is then applied in strips 10, 11, and 12, transversely to the folded blank, as represented 75 in Fig. 2.

The partially folded blank is then folded upon the transverse broken line 13 upon the gummed strips 10, 11 and 12, thereby bringing the gummed surface 14 of the sealing flap 6 and also the window opening 5 uppermost. By these folds, as described, two envelops are formed, the larger envelop represented at 15, Fig. 3, and the smaller represented at 16, laid upon the back side of the envelop 15. Suitable means are then applied to secure the closing flap 4, which in the present instance comprises a metallic fastener 17 provided with bendable prongs 80 18, 18, which are inserted through an opening 19 in the closing flap 4.

The method of attaching the closing flap 4 to the body of the envelop forms no part 85 of my present invention, and any suitable known device may be employed for that purpose. The bottom of the envelop 15 is closed by the act of folding upon the broken line 13, thereby forming an integral bottom for the envelop 15. In using the envelop bulky material of the second or third-class is inserted in the envelop 15 which is then closed by the detachable closing flap 4. Other matter subject to first-class postage is then placed in the envelop 16, which is sealed by 90 the gummed flap 6, the address upon said inclosure being aligned with the window opening 5 and serving as an address for both 100 105

envelops upon the back side of the envelop 15. The opposite or face side of the envelop 15 is thereby left free for a repetition of the address or for any printed matter to be 5 placed thereon.

I claim,

1. A two compartment envelop formed from a single blank comprising a body portion, provided with an ungummed closing 10 flap at one of its ends, a side flap of the same width and length as the body portion, provided with a gummed closing flap at its end opposite the closing flap of the body portion, a narrow side flap on the opposite side of the 15 body portion, said side flaps being folded on said body portion and united at their edges to form a tubular inclosure open at its ends, folding said tubular compartment transversely near one of its ends to bring the 20 gummed surface of said gummed closing flap outermost, thereby forming two compartments of unequal size, with the larger compartment provided with an ungummed closing flap and the smaller compartment 25 having a gummed closing flap, and with said compartments united by adhesive material.

2. An envelop having two compartments of unequal size, with the larger of said compartments having an ungummed closing flap and the smaller of said compartments provided with an opening in its exposed face and having a gummed sealing flap, said envelop being formed from an integral blank, comprising a body portion having an ungummed flap at one of its ends and a window 30 opening near its opposite end, a side flap of substantially the same width as the body portion, provided with a gummed closing flap at its end opposite said ungummed closing flap, a narrow side flap on the opposite 35 side of the body portion, with said side flaps folded on the body portion and united at their edges to form a tubular inclosure open at its ends, said tubular inclosure being folded transversely near one of its ends to 40 bring the gummed surface of the gummed closing flap outermost and the window opening of the body portion in the outer 45 face of the smaller compartment.

Dated this 29th day of November, 1919. 50

CHARLES E. CATHER.
